UNITED STATES PATENT OFFICE.

BENEDICT WOLTER AND ALFRED C. BROWN, OF ROCK ISLAND, ILLINOIS.

TRACK-LUBRICATOR.

1,334,065.

Specification of Letters Patent. Patented Mar. 16, 1920.

Application filed September 20, 1919. Serial No. 325,080.

To all whom it may concern:

Be it known that we, BENEDICT WOLTER and ALFRED C. BROWN, of Rock Island, in the county of Rock Island and State of Illinois, have invented certain new and useful improvements in Track-Lubricators; and we do hereby declare the following to be a full, clear, and exact description of the invention, such as will enable others skilled in the art to which it appertains to make and use the same.

Our object is to improve upon that class of devices adapted to apply lubricating oil from a street railway car to the guard rails at curves in the tracks.

We provide oiling devices mounted upon a fixed portion of the car truck preferably adjacent two opposite wheels. Each device comprises an oil chamber and a shoe constantly saturated with the lubricant. The device is swiveled and normally held with its shoe out of contact with the car wheel. The car body is provided with means responsive to the curvature of the track in either direction for turning the oiling device so that its shoe will be moved into contact with the wheel and so held while the car is traveling over the curve, the oil thus supplied to the wheel tending to lessen the wear of the wheel and track due to friction.

Figure 1 is a sectional view of one of the oiling devices, parts being in side elevation. Fig. 2 is a plan view of the actuating means on the car body.

We have shown the oiling device mounted upon a rigid frame 1 forming part of the car truck so that it will be constantly maintained in fixed bodily relation to the wheel 2. The oiling device consists of a chamber 3 adapted to contain the lubricant and formed at its lower end with a hollow neck 4 at the extremity of which is a shoe 5 adapted to lie adjacent the inner face of the wheel flange. We especially seek to avoid transmitting the oil to the tread surface of the wheel, resulting in slippery tracks. We aim to supply it only to the inner face of the flange which contacts with the guard rails at the curves of street railway lines.

Within the neck 4 is absorbent material 6 such as cotton waste. A screen 7 prevents this material from working into the oil chamber. The shoe is provided with a pad 8 in contact with the absorbent material. Thus the oil is free to feed from the chamber 3 through screen 7 and the absorbent

material 6 to the pad to maintain the shoe constantly saturated.

We have shown the neck 4 swiveled upon a post 9 rigid on frame 1. This evenly balances the weight of the oiling device as an entirety. A pin 10 is received by the post and provided with a fixed ring 12 movable in a groove formed in the post. This tends to promote the even balance. The pin 10 projects from a thickened surface 13 on the under face of the neck and between this surface and the top of the post is a bearing ring 14.

A spring 15 shown secured to the post 9 and to the base of the oil chamber normally holds the shoe of the oiling device out of contact with the wheel.

To automatically effect the contact of the shoe with the wheel we provide the following instrumentalities:—The under face of the car body is provided with two arcuate spring plates 16, 17, oppositely disposed and each having one end secured to the car body and the other end free. A shaft 18 of substantially T-shape is rigidly secured to the oiling device. It is shown extending vertically from the neck 4. Its lateral arms 19, 20, are adapted for engagement with the contiguous spring plates 16, 17, as the car truck turns on its swivel connection with the car body when traveling over a curve. As illustrated the lateral arm 19 lies contiguous to spring plate 16 and arm 20 is adjacent plate 17. Thus whether the car turns to the right or left, and the truck carrying the oiler follows the curvature of the track and turns on its swivel, one of the arms 19 or 20 will contact with its spring plate and the oiling device will be turned against the tension of spring 15 to effect contact between the shoe 5 and the car wheel. As the car reaches a straight track and the truck alines with the body the spring plate will disengage the arm and spring 15 will remove the shoe from the wheel. The action of the yielding spring plates prevents sudden jars that might break or derange the parts.

We preferably employ two of the described apparatus, one for each front wheel of the forward truck.

We claim as our invention:

1. Means for automatically lubricating railway tracks, comprising a car truck and a car body, an oiling device swiveled upon a fixed portion of the truck and consisting of an oil chamber and a shoe normally con-

tiguous a car wheel, with means for maintaining a constant supply of oil from said chamber to said shoe, means tending to hold said shoe out of contact with said wheel 5 when the car is traveling on a straight track, a pair of arcuate spring plates carried by the car body, and a shaft fixedly secured to said oiling device and having a pair of lateral arms adapted to be engaged by said plates as the car turns to the right or left 10 to turn said oiling device, and cause said shoe to engage the wheel.

2. In an apparatus of the character described, the combination with a car body having a pair of arcuate spring plates oppositely disposed and each secured at one end and having its other end free, of an oiling device swiveled upon a fixed portion of the car truck, and means actuated by one or the 15 other of said spring plates when the car is traveling upon a curve for rendering said oiling device operative.

3. In an apparatus of the character de-

scribed, the combination with a car truck having an oiling device swiveled thereon, 25 and a T-shaped shaft fixed to said oiling device, of a car body having a pair of plates adapted to engage the lateral arms of said shaft when the car is traveling upon a curve to render said oiling device effective. 30

4. In an apparatus of the character described, the combination with a car truck having a fixed frame member, a post secured thereon, an oiling device comprising an oil chamber, a shoe, and an intermediate neck 35 swiveled upon said post, and a T-shaped shaft extending vertically from said neck, of a car body having a pair of plates adapted to engage the lateral arms of said shaft when the car is traveling upon a curve to 40 render said oiling device effective.

In testimony wherof we have signed this specification.

BENEDICT WOLTER.
ALFRED C. BROWN.
